PACKAGING MACHINE

Fred West, Brooklyn, N. Y., assignor to S. Gumpert Co., Inc., Brooklyn, N. Y., a corporation of New York

Application May 22, 1935, Serial No. 22,700

3 Claims. (Cl. 93—6)

This invention relates to apparatus for packaging materials and particularly to apparatus for closing and sealing the ends of a container of cardboard or the like.

5 The object of the invention is to provide packaging apparatus simple in form and inexpensive in cost, and adapted to receive the package at one end and to automatically deliver it in completely sealed condition at the other.

10 Further objects of the invention, particularly in the automatic application of the adhesive and the simple guide means for subsequently folding and retaining the sealing flaps in place during the preliminary setting will appear from the following specification taken in connection with the accompanying drawings in which

Fig. 1 is a plan view of one embodiment of the invention with entrance and discharge ends broken away to shorten the space occupied by the figure;

20 Figs. 2 and 3 are vertical sectional views taken on the lines 2—2 and 3—3 of Fig. 1;

Fig. 4 is a vertical longitudinal sectional view of the apparatus shown in Fig. 1; and

25 Fig. 5 is a transverse vertical sectional view taken on the line 5—5 of Fig. 4.

In the specific embodiment of the invention shown in the drawings main frame supports F are mounted on legs 10, 11 and connected by cross pieces 12, 13, 14, 15, and 16. The cross pieces 12, 30 13, 14, and 15 are spaced above frame members F by bushings 17 through which pass the fastening bolts 18. A center strip 28 extends longitudinally along the middle of these cross pieces 12, 35 13, 14, and 15 and overhangs at the entrance end of the machine (left end of Fig. 4) and serves to support the trackway and feed chain for the packages.

The package trackway is formed by parallel 40 strips 19, 20 spaced apart and guiding the feed chain 21 between them, the feed chain 21 sliding on the center strip 28 and around the drive sprocket 22 and return idler 23 and an entrance idler (not shown). The drive sprocket 22 is fastened to cross shaft 25 rotating in bearings 26 on frame members F and driven from the main drive shaft 27 by chain 29 and sprockets 30, 31. The main shaft 27 carries the pulley 32 driven by belt 33.

45 50 In the machine shown the package operated on is a box B, square in section, and having four flaps at each end. The box is filled and three of the four flaps at each end are folded down and the box is placed in the conveyor with the fourth open flap 35 at each end protruding outward hori-

zontally at the top (Fig. 2) and the third flap 36 at each end extending vertically upward from the lower edge. The box is conveyed in this condition into the machine, side guide means being provided to hold the box ends closed while the 5 last flaps are coated with an adhesive and folded down and pressed in place to seal the package.

The side guide means comprise side bars 40 adjustably supported by brackets 41 from posts 42 on cross piece 12. The box B in the condition 10 above described is placed on the trackway strip 19, 20 between side bars 40 and with its flaps 36 in contact with said bars while the outermost flaps 35 extend outward above these bars. The box after insertion is engaged by one of the feed 15 lugs 45 of the chain 21 and moved along trackway 19, 20 and passes under the top bar 46 adjustably carried at one end by cross piece 47 extending transversely between posts 42. The other end of this top bar 46 is adjustably supported 20 from the cross pieces 48, 49 spanning posts 50, 50 and 51, 51 on cross bars 14, 15.

The travel of each chain lug 45 carries its box into the machine and brings the outwardly extending flaps 35 against the adhesive supplying 25 rolls 55 mounted on shaft 27 and dipping in adhesive liquid in tank T suspended underneath the rolls as shown. At the top of the rolls 55, the pressing rollers 57 are positioned on transverse shaft 58 mounted in brackets 59 on cross piece 30 13, these rollers 57 being closely adjustable to clear the peripheries of rolls 55 sufficiently to avoid picking up any adhesive while at the same time acting to force the flaps 35 in uniform contact with the surfaces of the rolls 55.

The side guides 40 are terminated just short of rolls 55 and replaced by wire guides 60 strung across from side bars 40 to the side plates 61 bolted by flanges 62 to the cross piece 14 on the delivery side of rolls 55.

40 The side flaps 36 of box B are thus held closed to and through the rolls 55 and until covered by the folding down of the outermost flaps 35. Following the coating of the under surfaces of these flaps 35 with the adhesive the flaps are engaged by the closing bars 62, 63 adjustably supported by rods 64 from posts 50, 51 and are bent as shown to contact with the tops of the flaps 35 and turn and press them gradually downward as the box B passes out of the rolls 55. 50 Then at the point P on each side, these bars 62, 63 close the flaps 35 against the underlying flaps with the adhesive acting to cement the contacting surfaces and the continued movement of the box B draws the closed flaps along the continuation 55

of the bars 62, 63 for a considerable distance before the box is delivered to the belting conveyor which seizes the box ends in a broad distributed grip acting to press all contacting parts of the flaps into binding engagement.

A sub-frame *f* is supported by cross piece 16 and legs 66 and carries the bearings 67 for the vertical shafts 68 of the pulley idlers 69 around which belts 70 run on each side. The drive pulleys 71 for these belts are on the vertical shafts 72 in bearings 73, 74 of cross pieces 16, 75 of the main frame. These shafts 72 are driven from shaft 76 by bevel gear sets 77, the shaft 76 being chain driven as shown from shaft 25 and supported in bearings 78 on legs 10, and the speed of the drive is preferably sufficient to receive and convey the boxes B out of contact with each other. The inner lengths of travel of the belts 70 are provided with flat backing strips 87 adjustably and resiliently supported by brackets 88 from the sub-frame *f* and acting to maintain the belts 70 in flat contact with the ends of the boxes while the adhesive is setting. Angle bars 80 on posts 81 between belts 70 form a supporting track for the boxes as they are borne along by the belts, and the adjustable belt-tensioning idlers 82 mounted on the adjustably pivoted bracket arms 83 maintain the proper tautness of the belting 70 on each side.

The boxes B ready for sealing are placed in the conveyor at the entrance end and picked up by the chain lugs 45 and carried along to the adhesive applying rolls 55, where the under surfaces of the extending flaps 35 are coated with adhesive. After this the closing bars 62, 63 wipe the flaps 35 downward against the ends of the box, the inward bending of these closing bars being reached at approximately the point P, after which the bars incline downward to provide a further downward wiping movement against the closed flaps, after which the bars are parallel and horizontal to hold the ends closed and deliver the box in closed condition to the final belt conveyor and sealing device. This belt conveyor with its belting 79 on each side may be extended as desired and is long enough to insure a preliminary setting of the adhesive and a permanent closing of the box.

All the operators have to do is to insert the boxes at the entrance end of the apparatus and receive them in finally closed condition at the

opposite end. While the invention has been described in connection with apparatus adapted to close and seal both ends of the package, it is obvious that the apparatus may be modified or operated to close only one end of the box, the other end being closed or left open as desired.

I claim:

1. In package sealing apparatus the combination with a conveyor for carrying a package with a closed and open flap at each end, of a guide 10 at the side of the conveyor for holding the closed flap closed, a roller carrying adhesive at the side of the conveyor beyond said guide, a closing bar beyond said roller for closing down the open flap, and a relatively small diameter 15 guiding wire adjacent the roller stretched for a distance between the guide and closing bar, whereby said roller may be located very close to the end of the package and apply adhesive over a large area of the open flap. 20

2. In package sealing apparatus the combination with a conveyor for carrying a package with closed and open flaps at each end, of a guide at each side of said conveyor for holding closed some of the flaps at each end of the package, a 25 roller carrying adhesive located beyond each guide, a closing bar beyond the roller at each side of the conveyor for closing down an open flap, and a relatively small diameter wire stretched for a distance between the guide and closing bar 30 adjacent each roller, whereby said rollers may be carried very close to the ends of the conveyor package and apply adhesive over a large surface of the open flap.

3. In package sealing apparatus the combination with a conveyor for carrying a package with closed and open flaps at each end, of a guide at each side of said conveyor for holding some of the flaps closed, a roller carrying adhesive beyond each guide, a short side plate beyond each 40 roller and a closing bar beyond each side plate, said closing bar curving near the outer edge of each side plate and extending along the side of the conveyor whereby the open flap at each side of said package is guided between said side plate and closing bar and is closed to the sealing position, and a relatively small diameter guiding wire stretched between the guide and side plate at each side of said conveyor whereby each 45 roller may be located close to the conveyor. 50

FRED WEST.
